UNITED STATES PATENT OFFICE.

FRANCIS C. OSBORN, OF DETROIT, MICHIGAN.

CONTAINER-BODY-FORMING MACHINE.

996,122.

Specification of Letters Patent. Patented June 27, 1911.

Application filed January 20, 1908. Serial No. 411,804.

To all whom it may concern.

Be it known that I, FRANCIS C. OSBORN, a citizen of the United States, and a resident of Detroit, in the county of Wayne and State of Michigan, have invented a new and Improved Container-Body-Forming Machine, of which the following is a specification.

My invention relates to means for reducing the diameters of the ends of tubes which are intended to form the body portions of cylindrical receptacles in order that when the heads are slipped over the ends of the tubes the flanges of the heads will not project laterally beyond the bodies of the receptacles.

The object of my invention is to provide a machine which will rapidly and automatically reduce the diameter of the tubes formed from fibrous material or metal so as to adapt such tubes for forming the body portions of cans or other receptacles.

My invention consists in tube holding means in combination with means for reducing the diameters of the ends of the tubes.

It further consists in the combination of an expansible mandrel, and means to reduce the diameters of the ends of tubes, the reducing means and mandrel being revoluble relative to each other.

My invention further consists in the combination of a tube carrier, means for feeding the tubes thereto, means to hold the tubes, means to reduce the diameter of the ends of the tubes, and means to remove the tubes from the tube carrier after the ends of the same shall have been properly reduced.

In the accompanying drawings, Figure 1 is a vertical, longitudinal, central, cross section of the machine. Fig. 2 is a plan of the same. Fig. 3 is a vertical cross section on the line A—A of Fig. 1. Fig. 4 is a cross section of the tube mandrel and reducers in the same plane as Fig. 1 on a larger scale. Fig. 5 is a view of a cylindrical box, part of it being broken away. Figs. 6 and 7 are views of the lower sides of the main operating cams. Fig. 8 is a view of the feeding and discharging mechanism on the line

B—B of Fig. 1. Fig. 9 is an end view of 50 the frame of the machine. Fig. 10 is a cross section on the line C—C of Fig. 4.

Similar reference characters refer to like parts throughout the several views.

Cylindrical boxes having cups slipped 55 over the ends thereof are very common. It has always been difficult to properly paste labels on these boxes because the flanges of the heads or ends projecting beyond the cylindrical surfaces of the body. My improved machine is adapted to so reduce the 60 diameters of the ends of the tubular bodies of this type of boxes that the flanges of the heads or ends may be so fitted to the reduced portions, that the outer surfaces of 65 the flanges and of the body will be practically one continuous cylinder.

My improved machine consists of a pair of frames connected by longitudinal bars and a central shaft upon which the reducing means 70 and the tube carriers are mounted. The reducing means each consist of an expansible mandrel adapted to receive the tubes from the tube carrier and two cup shaped reducers which are adapted to revolve in opposite directions over the ends of the tubes to reduce 75 the diameters of the same. Means are also provided to remove the finished tubes from the mandrel and discharge them from the machine. The tube carrier is provided with 80 pockets for each set of reducing means, the number of such reducing means depending upon the size of the machine.

In the accompanying drawings the two end frames 1 are connected by a shaft or bar 85 2 at their tops, a main shaft 3, and two connecting bars 4. Revoluble on the main shaft 3 are three sleeves 5, 6 and 7. A pulley 8 on the sleeve 5 and the pulley 9 on the sleeve 7 are driven in opposite directions at the same 90 speed by belts from the same counter shaft.

Extending across the shafts 4 is a frame 10 in which is mounted a shaft 11. On one end of the shaft 11 is a gear 12 which meshes with the pinion 13 secured to the sleeve 7. 95 On the other end of the shaft 11 is a pinion 14 which meshes with the gear 15 that is secured to the sleeve 6. Secured to this

sleeve 6 are the tube carrier 16 and the disk 17. As the gear 15, the disk 17 and the tube carrier 16 are all rigidly connected together, there is no possibility for them to get out of line with each other.

Secured to the gear 15 are the brackets 18 which carry the tubes 19 as shown in Fig. 1. Secured to the disk 17 are the brackets 20 in which are slidable the shafts 21. Slidably 10 and revolvably mounted on the tubes 19 are the sleeves 29, on one end of which are secured the pinions 21^a which mesh with the gear 22 secured to the sleeve 7. On the other end of these sleeves are cup shaped 15 reducers 23, preferably from hardened tool steel. On the ends of the shafts 21 are similar cups 24 which form the reducers for the other end of the container tubes.

Referring now, especially, to Fig. 1, it 20 will be noticed that the tube 19 is rigidly mounted in a bracket 18 secured to a revolvable gear 15, and that on this tube 19 is revolvable and slidable a sleeve 29 which is revolved by means of the gear 22. The shaft 25 21 is provided with a key 25, and is slidable through and revolvable with a pinion 26 which meshes with a gear 27 on the sleeve 5. By these means, (the gears 27 and 22 revolving in opposite directions and the disk 17 30 and gear 15 being connected together) the reducers will revolve around the shaft 3 in line with each other.

Referring now to Figs. 4 and 10 it will be seen that the tube 19 extends into the collapsible mandrel and has disks 30 secured, one to its outer and one to its middle portion. These disks extend laterally to form cylinders 31. Between the disks 30 the collapsible mandrel is supported, and consists 35 of four parts 32, the ends of which parts are guided between the disks 30, and are provided with guide screws 33 which are movable in the slots 34 in the disks. Springs 35 connect to these parts 32 and to the tube 19. 40 The ends of these parts 32 have tongues 36 provided with beveled edges, which enter slots 37 in the tube 19. Longitudinally movable in the tube 19 is a plunger 38 having conical portions 39 adapted to engage 45 the inclined edges of the tongues 37. When this plunger 38 is moved outwardly, that is to the left in Fig. 4, the mandrel parts 32 will be expanded, and when the plunger is retracted, the mandrel will collapse under 50 the action of the spring 35. In Fig. 4 the mandrel is shown in expanded position. The disk 40 at the end of the plunger prevents the same from slipping out. The tube 41 shown in Fig. 4 is slipped over the mandrel 55 in a manner which will be explained later. The plunger 38 is then moved out, expanding the mandrel to tightly engage

the inner side of the tube. The two cups 23 and 24 are then moved toward each other and as they revolve they will slip onto the 60 ends of the tube and reduce its diameter in the manner shown in Fig. 4. As these cups revolve in opposite directions, there will be little tendency for the tube to turn on the mandrel. The inner edges of the cups are 70 slightly tapered so that they will engage over the ends of the tubes. After the cups have revolved over the ends of the tubes a sufficient number of times to insure the reduction in diameter remaining permanent, 75 the cup 23 and then the plunger 38 are withdrawn thus first freeing the tube from the cup and then freeing it from the holding pressure of the mandrel. The cup 24 is then withdrawn carrying with it the tube 80 from the mandrel.

The mechanism for carrying the tubes and for operating the collapsible mandrel and the reducing means are as follows: The tube carrier 16 is formed by two disks 43 having 85 hubs 44 secured to the sleeve 6. The tubes travel down a guide 47 and are permitted to fall into the notches cut in the disks 43. To position the tubes spring held pins 48 are mounted in lugs 49. Other lugs 49 support 90 the spring held rods 50, on the outer ends of which are secured the flat fingers 51. The tubes falling into the notches in the carrier are positioned by these pins and fingers as shown by the dotted lines in Fig. 1. The 95 tubes are then pushed onto the mandrel as follows. Mounted on the rods 4 is a frame 53 which supports a bracket 54 on which is mounted a drum 55 which surrounds the sleeve 5. Secured to this drum are two 100 cams 56 and 57 which are adapted to engage the knobs 58 on the outer ends of the shafts 21 to move the cups 24 in and out as these knobs travel around the drum. It will be seen in Figs. 1 and 2 that when a shaft 21 is at the upper side of the drum, the cup 24 is drawn back to permit a tube to fall into a notch in the carrier. Further rotation of the carrier and disk 17 causes the cam 56 to push the shaft 21 inwardly until the cup 24 105 engages over the flange 31. In this movement the tube is pushed out of the notch in the tube carrier onto the mandrel, the spring held fingers 51 and pins 48 permitting the beveled edges of the cup to push them back. 110 After the revolving cup has accomplished its purpose it is withdrawn by the cam 57, the cup carrying back with it the tube into the notch in the tube carrier from whence it is ejected as will be described later. To prevent the tube being retained by the cups 24 after it has reached the proper position in the carrier, an ejecting disk 59 is mounted 115 in the cup 24 and connected to the plate 60

by means of pins 61. As the cup 24 is reaching the outward limit of its movement the plate 60 will contact with the disk 17 and force the ejecting disk outward as shown in 5 the upper part of Fig. 1.

Secured to the frame 10 and cross shaft 2 is a bracket 63 which carries the drum 64. This drum has three cams secured to it, the cam 65 to move the cup 23 in and out, and 10 the cams 66 and 67 to operate the plunger 38. From Fig. 2 it will be seen that until the end of the first quarter of the revolution of the sleeve 6, the plunger 38 and sleeve 20 are not moved longitudinally, that during this time the cup 24 is moving the container body over the collapsible mandrel. At the end of the first quarter and beginning of the second quarter, the cam 66 moves the plunger 38 inward, expanding the parts 15 32. During this second quarter the cams 56 and 65 (see Figs. 6 and 7) are moving the cups 23 and 24 toward each other, which cups will reduce the diameters of the ends of the container body 41 as shown in Fig. 4, the parts reaching the positions shown in 20 Fig. 4 just before the end of the second half. The parts remain in this position for a short time and then again move, the head 68 at the end of the plunger 38 passing the cam 66 and engaging the rear face of the cam 67. While the springs 35 and the inclined 25 ends of the tongues 36 usually push out the plunger, the cam 67 is a good safety device. The cam 65 is chiefly a projecting flange which fits in a groove 69 in the hub of the gear 21^a. The inclined portion 70 of this cam will withdraw the cup 23 immediately after the end of the second half of the revolution of the tube carrier. The tube 30 being free from the cup 23 and the mandrel having collapsed, the action of the cam 57 on the head 58 on the end of the shaft 21 will carry the tube back into its notch in the tube carrier.

Instead of forming the plunger 38 solid, a spring relief may be employed as shown in the upper part of Fig. 1, by means of which slight differences in the internal diameters of the tubes are provided for.

To eject the finished tubes, a sleeve 70 is loosely mounted on the shaft 2 and is held in position by the pin 73 and by the spring 71, one end of which is secured to this sleeve, and the other to the collar 72. A finger 74 projects into the paths of the pins 75 carried by the cams 76 on the inner side of the gear, 15. Arms 77 (see Fig. 3) project forward from the collars 78 on the sleeves 70, which arms are not shown in Fig. 1, being 55 cut away for the sake of clearness. The pins are so positioned that the arms 77 will be drawn back to the position indicated by

dotted lines in Fig. 3 and released just as a tube is brought to the position there indicated, the action of the spring 71 causing the 60 arms to snap the tube out of the notch in the carrier 16 and out of the machine.

While the finished tube is usually carried off the mandrel by means of the cup 24, means are provided for removing the tube 70 should it fail to move. A frame is secured to the shaft 2, comprising end pieces 80 and longitudinal members 81 and 82. The guides 47 are secured to the longitudinal members. A shoe 83 is slidable on the bar 75 81 and is normally held to the right by the spring 84. Projecting down from this shoe is a pin 85, normally in the path of the cams 76 on the gear 15. An arm 86 projects rearwardly from the lower side of the shoe 83 (Fig. 8) and carries a finger 87 which projects through a slot in the rear end of the stripper arm 88 which is pivoted on the bar 81 at 89. The outer end of the arm 88 is broken off in Fig. 1 for clearness. 85 When a cam 76 passes the pin 85, which is secured to the shoe 83 that is slidable on the longitudinal member 81, the pin and shoe will be moved to the left, and thereby the upper end of the stripper arm 88 which is 90 pivoted to the member 81 will be swung to the left through the action of the pin 87 on the arm 86 that is secured to the shoe 83, and the lower end to the right (Fig. 2) and will remain at the right end of the mandrel until the cam passes the pin 85 when the spring 84 will swing the arm back to 95 normal position. This occurs just as the finished tube reaches the position indicated by dotted lines in Fig. 3, or just after the 100 arms 77 have been swung back through the action of a pin 75.

The tubes to be formed roll down the inclined guides 47 and fall onto the edges of the disks 43 of the tube carrier where they 105 remain until a notch receives them. They are prevented from rolling down by the arms 77. To prevent the edge of a second tube from getting into the path of a cup 24 during its movement to place the tube 110 just before it over the mandrel, means are provided for lifting the second tube out of the path of the cup 24. A light shaft 90 is pivoted in the arms 77 and a finger 91 is secured to one end of this shaft in the path 115 of the pins 92 on the disk 17. Other fingers 93, similar to finger 91 are secured to this shaft so that when a pin 92 swings the finger 91 rearwardly, the fingers 93 will engage said second tube and lift it out of the way 120 of the cup 24. A spring 94 holds the parts in normal position. Plates 95 secured to the inner sides of the arms 77 prevent the tubes from moving endwise.

Having now explained my construction, what I claim as my invention and desire to secure by Letters Patent is:—

1. In a tube forming machine, the combination of a frame, a tube carrier, collapsible mandrels, reducing means, and driving mechanism for the various parts, whereby the tubes are slipped onto the mandrels, the mandrels are expanded, the reducers engaged over both the ends of the tubes simultaneously, the mandrels collapsed, the tube reducers withdrawn and the finished tube discharged from the machine.
2. In a tube forming machine, the combination of revoluble expansible holding means for the tube, a revolving reducer adapted to engage the end of the tube and reduce its diameter, and means to operate the reducer.
3. In a tube forming machine, the combination of a frame, a horizontal shaft mounted therein, a tube holding device revoluble about said shaft, and reducing means adapted to engage the tube when on the tube holder in order to reduce the diameter of the end, a disk revoluble around said shaft and adapted to support said reducing means, means to operate said reducing means, and gears to revolve said disk and said holding means about the shaft.
4. In a tube forming machine, the combination of a collapsible mandrel adapted to receive the tubes, solid cups adapted to engage over the outer ends of the tubes to reduce their diameters, and means to revolve said reducers in opposite directions.
5. In a tube forming machine, the combination of a collapsible mandrel adapted to receive the tubes, a plunger adapted to expand the mandrel and springs to collapse the same, a cup adapted to engage over one end of the tube mandrel to reduce the diameter of the end of the tube thereon, gears adapted to revolve the cup, and cams for moving the cup to and from the mandrel.
6. In a tube forming machine, the combination of a collapsible mandrel adapted to receive the tubes, a plunger adapted to expand the mandrel and springs to collapse the same, cups adapted to engage over the ends of the tube mandrels to reduce the diameters of the ends of the tubes thereon, gears adapted to revolve the cups in opposite directions, and cams for moving the cups to and from the mandrels.
7. In a tube forming machine the combination of a frame, a tube carrier, a mandrel carrier revolubly mounted in said machine; tube mandrels each comprising a sleeve provided with flanged disks, four expansible and collapsible segments of a cylinder mounted between said disks, a slidable plunger having

inclined surfaces to expand the segments and springs to collapse said segments; means to operate said plungers, reducers to engage the tubes on the mandrels, and driving mechanism for the various parts.

8. In a tube forming machine, the combination of a frame, a mandrel carrier, a tube carrier, and a reducer carrying disk mounted in said frame to revolve together, means for feeding tubes to said tube carrier, slideable shafts mounted in said disk, reducing cups mounted on the inner ends of said shafts, mandrels mounted on the mandrel carrier, cams adapted to engage the shafts to slide the tubes onto and off the mandrel carrier, and means to drive said shafts so as to reduce the diameter of the ends of the tubes.

9. In a tube forming machine, the combination in a machine for reducing the diameters of the ends of tubes, of means for carrying the tubes, of collapsible mandrels for holding the tubes while being reduced, of reducing means adapted to move on and off the ends of the tubes, the tube carrier, the mandrels and the reducers being revoluble around a common axis, cams to so move the reducers that the tubes will be moved from the carrier onto the mandrel and there remain for a short period of time, the reducers then separating, the tube being withdrawn from the mandrel by one of the reducers, a cam to expand the mandrel after the tube has been slipped on, and to collapse the mandrel so the tube may be withdrawn, and driving mechanism to revolve the reducers for the opposite ends of the tubes in opposite directions.

10. In a tube forming machine, a frame, a shaft mounted therein, a sleeve revoluble thereon, a tube carrier, a reducer carrier and a reducer and mandrel carrier mounted on said sleeve, means to revolve the same about the shaft, gears to revolve the reducers, cams to move the reducers in and out, means to eject the finished tubes from the carrier, and means to strip the tubes from the mandrels.

11. In a tube forming machine, the combination of means to hold the tube from turning, solid cups adapted to engage over the outer ends of the tubes to reduce their diameters, and means to revolve said reducers in opposite directions.

12. In a tube forming machine, the combination of means to hold the tube from turning, means adapted to engage over the outer ends of the tubes to reduce their diameters, and means to revolve said reducers in opposite directions.

13. In a tube forming machine, the combination of a mandrel for holding the tube from turning, means adapted to engage over

the outer ends of the tubes to reduce their diameters, means to revolve said reducers in opposite directions, and mechanism for moving said reducers toward and from each other.

14. In a tube forming machine, the combination of a frame, a tube carrier revolubly mounted thereon, a mandrel carrier also revolubly mounted in said frame, tube mandrels carried by said frame each comprising an expansible shell and means to expand the shell, revoluble reducers mounted on the mandrel carrier adapted to engage the ends of the tubes, and means for actuating the 10 various parts.

15. In a tube forming machine, the combination of a tube carrier, a cylindrical sleeve adapted to engage over one end of a cylindrical tube to change such end to a cylinder of smaller diameter, means to revolve the reducer, and means for supporting the tube while being reduced to prevent distortion. 20

In testimony whereof I have signed this specification in the presence of two subscribing witnesses.

FRANCIS C. OSBORN.
